UNITED STATES PATENT OFFICE.

JAMES T. KING, OF TORONTO, ONTARIO, CANADA.

ELECTROLYTIC APPARATUS.

1,254,045.

Specification of Letters Patent. Patented Jan. 22, 1918.

Application filed April 19, 1917. Serial No. 163,226.

To all whom it may concern:

Be it known that I, JAMES THOMAS KING, of the city of Toronto, in the county of York, Province of Ontario, Canada, have invented certain new and useful Improvements in Electrolytic Apparatus, of which the following is a specification.

This invention relates to apparatus particularly adapted for conducting electrolytic assays, and my object is to devise apparatus in which a plurality of assays may be carried on at the same time with the electrolytes in series, in which any one receptacle of electrolyte can be withdrawn from 10 operation with its electrodes without breaking the circuit through the electrolyte of the remaining receptacles, and in which effective stirring of the electrolyte is obtained without moving either electrode and without 15 using any special stirring device.

I attain the objects above set out and others which will hereinafter appear by means of the constructions hereinafter described and illustrated in the accompanying drawings in 20 which—

Figure 1 is a front elevation of my improved electrolytic apparatus;

Fig. 2 a horizontal section of the same;

Fig. 3 a plan view partly broken away;

Fig. 4 a rear elevation; and

Fig. 5 a vertical section of the receptacle support, and its mountings.

Fig. 6 is an enlarged side elevation partly in section of the electrode clamps.

In the drawings like numerals of reference indicate corresponding parts in the different figures.

The basis of the present invention is the arrangement of the apparatus so that the 40 receptacle for the electrolyte is rotated so as to obtain all the advantages of the stirring of the electrolyte while the electrodes remain stationary.

I therefore provide one or more supports 1 for the electrolyte receptacles such as 2. These receptacles will usually, of course, be cylindrical beakers. The supports are cup-shaped as shown to receive the beakers, and as the beakers may vary slightly in size, 45 each support is provided with elastic means adapted to engage the sides of the beaker.

In Fig. 5 I show rubber plugs 3 fitted in recesses in the inner face of the cup-shaped support. The inner edges of these plugs 55 protrude and yield more or less to suit variations in the size of the beaker. This sup-

port thus has a frictional grip of the beaker so that the latter will turn with the support.

The support is provided with a spindle 4 suitably journaled in a bearing 5. This bearing is vertically movable in a guide 6 secured to the base of the apparatus. The bearing is preferably tubular externally and a similar recess is formed for it in the guide, from which recess extends the vertical slot 65 7. A pin 8 is secured to the bearing 5 and extends through the slot, and on its outer end is threaded a nut 9. Between the nut and the guide is placed a washer 10, preferably of rubber metal-faced, for a purpose 70 which will hereafter appear.

It is evident that the pin 8 with its nut provides means whereby the receptacle support may be raised or lowered and held at any desired height. A rubber buffer 11 is 75 preferably provided at the upper end of the slot 7 to limit the upward movement of the receptacle support.

Above the receptacle support is located the electrode clamps 12. One jaw of each clamp 80 is stationary and the other jaw 13 is connected with a slide 14 movable in a guide 15. The upper end of this slide is upturned to form a finger grip 16. Between this finger grip and the guide is located a coil spring 17 85 which tends to move the movable jaw of the clamp toward the stationary jaw. The clamps are so arranged that one electrode will be held substantially in alignment with the axis of the spindle 4, and hence of the 90 electrolyte receptacle, while the other is offset.

The electrode 27 carried by the first mentioned clamp will usually be of a strip of rodlike form, while the electrode 28 carried 95 by the other clamp is preferably a cylinder or portion of a cylinder concentric with the axis of the electrolyte receptacle. Consequently, when the electrolyte receptacle with its liquid contents is rotated, the electrolyte 100 is in constant motion relative to the electrodes, but is not unduly agitated.

It is necessary, of course, that when the electrolyte receptacles and electrodes are not in co-operative position that the rotary movement of the electrolyte receptacle should cease. It is necessary, therefore, to provide means for driving the support which will automatically go out of gear when the support for the electrolyte receptacle is lowered. 110

The driving arrangement provided comprises a suitable motor such as the electric

motor 18. This motor, by means of a suitable pulley 19, drives the belt 20. This belt is carried around suitable guide pulleys 21 and extends lengthwise of the apparatus 5 transversely of the spindles 4 and adjacent thereto. Each electrolyte support is provided with a cone pulley 22, which, when the support is raised, will contact with the belt and be frictionally driven thereby.

10 The electrolyte clamps are connected in series in a suitable circuit 23. As the electrolyte in each receptacle normally forms part of the circuit, the circuit would be broken when an electrolyte receptacle is 15 lowered sufficiently to withdraw the electrodes from contact with the electrolyte. I therefore procure automatic means for establishing a shunt circuit around the electrode clamps of any receptacle which is so 20 lowered. These shunt circuits are indicated in dotted lines in Fig. 1, and the metal strips comprising them are shown more clearly in Figs. 2, 3 and 4.

Each shunt circuit 24 includes contact 25 plates 25 secured one at each side of the slot 7. When a support 1 is lowered sufficiently to break the circuit through the electrolyte in the receptacle carried thereby, the washer 10 which forms a contact piece establishes 30 an electrical contact between the two plates 25 so that there is no break in the main circuit through the remainder of the apparatus. In the drawings I show only two supports, but in actual practice a number more 35 will probably be employed.

From the above description it will be seen that I have devised apparatus which will satisfactorily attain the objects of my invention as set out in the preamble to this specification.

40 40 What I claim as my invention is:—
1. In electrolytic apparatus, the combination of suitably supported electrodes; a rotatable support for an electrolyte receptacle; 45 and means for rotating said receptacle support.

2. In electrolytic apparatus, the combination of suitably supported electrodes, one of 50 said electrodes being formed as a portion of a hollow cylinder; a rotatable support for an electrolyte receptacle; and means for rotating said receptacle support.

55 3. In electrolytic apparatus, the combina-

tion of suitably supported electrodes; a rotatable support for an electrolyte receptacle 55 formed as a cup provided with elastic holding means adapted to engage the sides of a cylindrical receptacle; and means for rotating said receptacle support.

4. In electrolytic apparatus, the combination of suitably supported electrodes; a rotatable support for an electrolyte receptacle; means for rotating said receptacle support; and means for axially adjusting the position of said support relative to the said electrodes.

5. In electrolytic apparatus, the combination of suitably supported electrodes; a support for an electrolyte receptacle mounted for rotation and adapted also to be moved 70 axially to and from the electrodes; a friction pulley connected with said receptacle; and a suitably driven means with which said friction pulley engages when said support is moved to a predetermined position 75 relative to the electrodes.

6. In electrolytic apparatus, the combination of suitably supported electrodes; a circuit including said electrodes; a shunt circuit normally open; and means connected 80 with the receptacle support whereby the movement of said support a predetermined distance from the electrodes closes the shunt circuit.

7. In electrolytic apparatus, the combination of two pairs of electrode clamps; spring actuated slides to which one clamp of each pair is connected; a rotatable support for an electrolyte receptacle; and means for rotating said receptacle support.

8. In electrolytic apparatus, the combination of electrode clamps; a support for an electrolyte receptacle; a spindle to which said support is connected; a bearing for said spindle; a guide in which said bearing 95 is vertically adjustable; a circuit including the electrodes; a shunt circuit normally open and including contact plates mounted on said guide; and a contact piece carried by said bearing adapted to engage the contact plates and close the shunt circuit when the said support is moved a predetermined distance from the electrode clamps.

100 Signed at Toronto, Canada, this 10th day of April, 1917.

JAMES T. KING.
